UNITED STATES PATENT OFFICE

CLEMENS CZAJKOWSKI, OF MILWAUKEE, WISCONSIN

SCREW CAP RETAINER

Application filed September 26, 1930. Serial No. 484,667.

This invention relates to an auxiliary structural feature embodied in the cap construction of a collapsible tube such as is employed for containing paste, creams and analogous 5 saponaceous materials.

As generally marketed, containers of this variety are in the nature of an elongated compressible tube having a screw-threaded discharge nipple or neck at one end and a rim-equipped screw-cap for detachable association with the neck. It is a matter of common knowledge that the cap is bodily removable and it is frequently lost or misplaced.

The purpose of the invention is to provide a means for permanently connecting the cap to the neck to avoid accidental misplacement of said cap.

In carrying the inventive conception into practice, I have provided a retainer characterized by exceeding simplicity and economy in construction and susceptible of affording a swivel elastic connection between the cap and the discharge neck.

In the drawings:

Figure 1 is an elevational view of a collapsible tube and cap embodying the improved cap retainer as designed in accordance with my inventive conception.

Figure 2 is a sectional view showing, in dotted lines, the open retained position of the cap.

Figure 3 is a detail view of the retainer per se.

The collapsible tube 4 is of conventional construction and includes a frusto-conical end 5 having a conventional screw-threaded discharge nipple 6. The cap is indicated at 7 and includes a gasket 8 and a fingergrip or ring 9. The improved retainer is generally designated by the numeral 10 and is formed from a single length of wire which is bent upon itself at one end to form an annular resilient clip 11. This is sufficiently resilient 40 to permit it to be snapped around the base portion of the neck 6 as shown in Figure 2.

The free end portion 12 is bent into substantial parallelism to the intermediate portion 13 and fastened in the rim portion of the 50 cap as shown in Figure 2. The part between

the portions 12 and 13 is fashioned to provide a coiled spring 14.

With this arrangement, it is obvious that the cap and the fastener 10 rotate as a unit when removing or applying the cap 7. When 55 the cap is disconnected from the threads the spring 14 comes into play to automatically swing it out from the dotted line position shown in Figure 2 where it is held conveniently out of the way of the discharge end 60 of the neck. It is an easy matter, however, to return the cap to its fastened position.

With this arrangement, the spring wire fastener is formed as an integral part of the cap and the annular ring or clip 11 is simply 65 snapped around the neck so as to afford the desired swivel connection between the retainer and the cap as shown in the drawings.

The device embodies features of surpassing merit. There are no sharp points or wire- 70 ends to stick into the fingers of the user or to become caught in the clothing. The device performs an unequalled achievement in swivelly connecting the cap with the neck so as to allow easy manipulation of the cap.

The retainer is thoroughly practical and the structural features are systematically arranged to permit it to fulfill the requirements of a device of this class in a highly satisfactory manner.

To open the cap, in Figure 2, simply unscrew the cap in the usual way, thus turning the retainer 9 around the neck as a unit with the cap. As the cap is completely unscrewed, it is automatically swung out to an out-of-the-way position as indicated in dotted lines. To 75 screw the cap back, simply bend the wire-end 12 over again and replace the cap as under ordinary conditions. It will be seen that the retainer does not interfere with 80 either the opening or closing operation, but constitutes an added feature of unusual importance.

It is thought that persons skilled in the art to which the invention relates will be 85 able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice if desired.

5 I claim:

In combination with a tube having a threaded neck and a cap threaded on the neck and having an enlarged rim provided with an opening passing out through a part of the 10 periphery of the rim, a wire bent intermediate its ends to form a coil, with leg portions extending from the coil, one leg portion fitting in the opening in the rim and the extremity of the other leg portion being bent 15 to form a snap ring for rotatably engaging the neck of the tube.

In testimony whereof I affix my signature.
CLEMENS CZAJKOWSKI.
